PROTECTOR CAP

John G. Baumgartner, Aurora, Ill.

Application February 25, 1942, Serial No. 432,287

6 Claims. (Cl. 120—84)

This invention relates generally to protector caps and in particular to a cap for covering the operating or exposed end of pencil devices.

The use of drawn metal caps for capping pencil devices and the like is well known. These metal caps have been used with ordinary lead pencils, for eyebrow pencils and for many other types of pencils where there was danger of the exposed or operating end of the pencil becoming broken from handling or storage, or of touching and possibly discoloring adjacent articles. The metal caps are usually formed in one piece and generally comprise a substantially conical portion closed at the tip or apex thereof and a cylindrical portion having an open end. The cylindrical portion adjacent the open end is usually split in an axial direction along one side thereof to provide for its being spread apart on insertion of a pencil therein. As a result the cylindrical body portion of the pencil is frictionally engaged by the cylindrical portion of the metal cap due to resiliency resulting from the split therein, whereby the cap is retained on the pencil and in a covering relation with respect to the operating end thereof. These prior art metal caps although generally satisfactory are rather expensive because of their metal construction and further are unadapted, without appreciable additional expense, to be colored or designed for harmonious blending with the coloring and design of the pencils with which they are associated.

It is an object of this invention, therefore, to provide an improved protector cap.

Another object of this invention is to provide a non-metallic protector cap for pencil devices.

Yet another object of this invention is to provide a non-metal protector cap for pencil devices which is relatively inexpensive in cost, readily adapted to be designed and colored to correspond with an associated pencil, and which is releasably retained on the pencil by frictional engagement therewith.

A feature of this invention is found in the provision of a plastic protector cap for pencil devices which is provided on the inner periphery and intermediate the ends thereof with a substantially rigid axially extending radially projecting portion having one end terminating in such periphery and which is tapered in a direction axially of the cap so as to frictionally engage a pencil device inserted within the cap.

Further objects, features, and advantages of this invention will become apparent from the following description when taken in connection with the accompanying drawing in which:

Fig. 1 is a complete assembly view of the protector cap of this invention with an associated pencil device;

Fig. 2 is a longitudinal sectional view of the protector cap taken approximately along the line 2—2 of Fig. 3; and

Fig. 3 is a transverse sectional view as seen along the line 3—3 of Fig. 2.

Referring to the drawing the cap 5 of this invention is shown in Figs. 1 and 2 being adapted for capping a pencil 6 having a cylindrical body portion 7 and a tapered or operating end E. For purposes of illustration the pencil 6 is shown as having a cylindrical body but it is understood that a pencil with a square or polygonal-shaped body can be protected in the same manner. The cap 5 is of a substantially tubular or sleeve form constructed in one piece and composed of "Bakelite" or like moldable material. The cap is comprised of a cylindrical portion 8 and a tapered or conical portion 9, the junction of these two portions being indicated at 10. The conical portion 9 is tapered inwardly away from the cylindrical portion 8 and is closed at the tip or apex end 11 of the cap. The opposite end 12 of the cap 5, and at the cylindrical portion 8, is open to receive the pencil 6 therein. Intermediate the cap ends 11 and 12 are axially extending substantially wedge-shaped ribs or ridges 13 formed on the inner periphery of the cap and projected radially thereof. The ribs 13 (Fig. 3) are angularly spaced about the cap and are substantially rigid relative to each other and to the cap portions 8 and 9. Each rib 13, at the end 14 thereof, terminates in the inner periphery of the cap and is tapered in an axial direction toward the closed cap end 11 at an angle depending upon the angle of the tapered end E of the pencil 7.

In one embodiment of the invention the cap 5 is about one and one quarter inches long, with the rib or wedge-shaped portions 13 being about a half an inch long and extended substantially equal distances to each side of the junction 10 of the cap portions 8 and 9. The cylindrical cap portion 8 has an inner diameter which is about one thirty-second of an inch greater than the diameter of the cylindrical body portion 7 of the pencil 6, or about $\frac{1}{32}$ " greater than the diameter of a circle through the outside points on a polygonal or square-shaped body. As is well known in the making of pencils the diameters of the same type pencil vary appreciably. The cylindrical portion 8, therefore, is adapted to accommodate pencils of like kind regardless of any slight variations in their relative diameters.

On insertion of the tapered pencil end E within the cap 5 through the open end 12 thereof, the rib portions 13 engage the pencil substantially at the large end of the tapered pencil end E or, as indicated at 17, at the junction of the tapered end E with the cylindrical body portion 7 so as to frictionally retain the cap 5 on the pencil. Because of the tapered or wedged construction of the ribs 13 all pencils adapted to be inserted within the open end 12 of the cap are frictionally engaged by the ribs regardless of any slight variations in their relative diameters or the relative angles of their tapered ends E. These variations, of course, position the small ends of the tapered pencil portions E of the pencils at slightly different points in the cap 5. However, sufficient space is provided at the closed apex end 11 of the cap to allow for these variations so that the cap is always frictionally retained on the pencil and in a protecting or covering relation with the operating end thereof. By virtue of this engagement of the wedge portions 13 with the pencil 6 there is accomplished a positive frictional holding of the cap on the pencil while providing for a free and easy removal of the cap from the pencil when the end E thereof is to be used.

From a consideration of the above description and drawing, therefore, it is seen that the invention provides a non-metal cap for pencil devices which is of a rugged construction and easily manipulated to a capping position. Since the cap is of a non-metal construction, and composed of a plastic material it can be readily colored or intricately designed to correspond with the design of the pencil without in any manner increasing the cost thereof. The tapered construction of the wedge portions 13 readily adapts the cap to a plurality of pencil devices having different sized diameters or tapered end portions without impairing the efficient capping function thereof. Although the wedge portions 13 have been described and illustrated as being plural in number and angularly spaced about the inside of the cap 5, it is apparent of course that a single wedge portion extending entirely about the inside of the cap may be used within the limits of this invention. It is also apparent, that in some instances the end 11 of the cap may be left open with the axial extension of the periphery of the cap providing sufficient protection for the operating end of the pencil.

Although the present invention has been described with specific reference to a particular embodiment thereof it is to be understood that it is not to be so limited since changes and modifications can be made therein which are within the full intended scope of this invention as defined by the appended claims.

I claim:

1. A protector cap for a pencil device, said cap comprising a cylindrical portion and a conical portion joined at their adjacent ends, with an axially extending wedge-shaped portion projecting inwardly of said cap at the junction of said cylindrical and conical portions, said wedge-shaped portion adapted to frictionally engage a pencil device to retain said cap thereon.

2. In a pencil device having a tapered end, a

one piece plastic cap for covering said one end comprised of a cylindrical portion and a tapered portion, a plurality of angularly spaced ridges radially projected within said cap and extended longitudinally thereof to each side of the junction of said cylindrical and tapered portions, said ridges on insertion of said tapered end within said cap through said cylindrical portion frictionally engaging said pencil device to retain said cap on said tapered end.

3. In a pencil device having a tapered end portion, a cap for covering said tapered portion, said cap being closed at one end and open at the other end thereof, an axially extending ridge on the inner surface of said cap tapered inwardly toward said closed end and having one end thereof spaced from said open end and terminating in said inner surface, said ridge engaging said tapered portion substantially at the large end thereof to frictionally retain said cap on said pencil device.

4. In a pencil device having a tapered end portion, a cap for covering said tapered portion comprising a cylindrical portion and a substantially conical portion tapered inwardly away from said cylindrical portion and closing said cap at one end thereof, said cap being open at the opposite end thereof, a plurality of ridges angularly spaced on the inner surface of said cap and extended axially thereof to each side of the junction of said cylindrical and conical portions, each of said ridges having one of their corresponding ends terminating in the inner surface of said cylindrical portion, said ridges on insertion of said pencil tapered portion within the cap at said open end frictionally engaging said pencil device substantially at the large end of said tapered end portion to retain said cap on said pencil device.

5. A protector-cap open at one end for fitting over one end of a pencil-like device to be frictionally retained thereon but adapted to be removed therefrom with a substantially straight pull, said protector cap being hollow on the inside and including on said inside a portion which is substantially straight longitudinally of the cap extending from said open end, a tapered portion extending longitudinally of the cap away from said substantially straight portion, and a projecting portion on said inside extending longitudinally of the cap over the area of the junction of said first two named portions and tapering inwardly into the cap in the longitudinal direction away from said open end.

6. A hollow protector-cap open at one end and adapted to fit over a pencil-like device which has a substantially straight body portion and a substantially tapered end portion extending therefrom with a junction portion therebetween, said cap on the inside thereof having a plurality of ridges extending substantially longitudinally of the cap, with each such ridge extending from a point spaced from the open end and tapering inwardly in the longitudinal direction away from said open end, with said ridges being adapted to frictionally engage a pencil-like device substantially at the junction portion of the device when the protector-cap is placed on such device.

JOHN G. BAUMGARTNER.
